UNITED STATES PATENT OFFICE

2,441,365

VACUUM CLEANER

Harley J. McAllister, Wheaton, Ill.

Application January 15, 1945, Serial No. 572,933

1 Claim. (Cl. 183—37)

1

My invention relates to vacuum cleaners and more particularly to the provision of a vacuum cleaner unit embodying a dust pan, a filter, a fan and a motor wherein the maintenance of the device is simplified and made more easy for the housewife.

It is the principal purpose of this invention to provide a vacuum cleaner wherein the dust pan is separated from the rest of the equipment and serves as a support therefor, and a seal being established between the dust pan and the suction unit by a rubber ring which serves also as a bumper.

It is a further purpose of my invention to provide a vacuum cleaner wherein a filter unit is separably set upon the dust pan and the suction unit is separably supported over the filter unit for ready removal to give access to the filter and the dust pan, all of the parts being held assembled in operation by a simple clamping device.

It is a further purpose of my invention to provide an improved filter and bumper unit for vacuum cleaners.

The nature and objects of my invention will appear more fully from the following description and the accompanying drawings wherein a preferred form of the invention is shown. It should be understood however that the drawings and description are illustrative only and should not be taken as limiting the invention except insofar as it is limited by the claim.

In the drawings:

Figure 1 is a vertical section through a suction cleaner embodying my invention;

Figure 2 is a sectional view taken on the line 2—2 of Figure 1, parts being broken away to illustrate the detailed construction; and

Figure 3 is a fragmentary sectional view taken on the line 3—3 of Figure 1.

Referring now to the drawings, my invention is embodied by a suction cleaner which comprises a pan shaped dust pan 5, a filter unit 6, a suction fan 7, a drive motor 8 and an enclosure 9 for the fan and motor. A handle 10 is mounted on the enclosure 9 and carries a switch 11 by which the motor 8 is controlled.

The dust pan 5 has an inlet at 12 to which a suction tube having a suitable dust collecting nozzle may be attached. This dust pan has its top edge rolled over as shown to provide a support for a resilient ring 14 which is a part of the filter unit 6. This ring 14 may be constructed of rubber, either natural or synthetic, or a similar material capable of making an air tight seal with the edge of the dust pan. The ring 14 has a lower chan-

2

nel 15 in which the turned over rim 13 fits. The ring also has an upper channel 16 which receives a spun-over edge 17 of the cover 9. The ring 14 has a rounded outer surface 18 which is grooved as indicated at 19 to receive a clamping and reinforcing wire band 20. The band 20 preferably is a wire spring and its function is to strengthen the ring 14. The spring 20 is fitted into the groove 19 to such an extent that it cannot contact furniture or walls that may be engaged by the outer rounded surface 18 of the ring 14. This outer surface serves as a bumper to prevent damage to furniture and similar articles.

The ring 14 serves to support the filter unit 6 in such fashion that the filter unit can be handled separately either from the dust pan or the suction unit so that in taking the device apart for removing the accumulated dust and dirt, the filter unit is entirely accessible for separate handling and cleaning. Likewise the dust pan is separable and replaceable, in fact, the dust pan may be used as a water receptacle when the suction device is used for scrubbing rugs and the like, and the filter would not be damaged with the water except insofar as moisture might be carried over in the stream of air. The filter unit includes a flat metal ring 21 which is inserted into the resilient ring 14, the ring having a slot 22 in its inner edge for this purpose. The ring 21 is larger in its outer diameter than the dust pan or the cover so that it actually extends into the hollow space 22a of the ring 14 between the parts 13 and 17. The ring 21 has an upturned flange 23 on which a filter cloth 24 is clamped by a split band 25. The filter cloth 24 has a supporting ring 26 thereon at a short distance above the clamped edge. The ring 26 is slightly larger than the band 25 and falls down over the band when the suction unit is not in operation. At its central portion the filter cloth 24 has a lifting strip 28 fastened thereon so that the strip can be used to carry the filter unit or to shake the unit.

The fan unit 7 is of a standard construction, comprising a shell 29 with a partition 30 therein. The shell has its top opened as indicated at 31 around its periphery and is adapted to support the motor 8. A ring 32 is provided on the motor, and this ring is cut out as indicated at 33 to allow air to pass upwardly. The ring 32 is welded to the top of the shell 29. The motor shaft carries fan blades 34 and 35. The shell 29 has a central bottom opening 36 through which the fan blades draw air. The shell 29 also serves as a support for a screen member 37 which may be made of relatively coarse wire screen or of an equivalent con-

struction which will serve to support the filter cloth 24 against the suction of the fan 7. The screen is carried on posts 38 of which there are four secured to the bottom of the shell 29.

The cover 9 is composed of two sections so arranged as to be readily separable to provide access to the motor and fan. A lower section 39 of the cover has an inturned upper edge 49 which provides a shelf upon which a ring 41 rests. The ring 41 is of rubber or other suitable cushioning material. It serves to support a flanged ring 42 that is welded on the shell 29. Rubber grommets 43 are pressed through suitable openings provided in the horizontally extending parts 40 and 42 to connect the shell 29 of the lower portion 39 of the cover 9. Screw bolts 44 are used to compress the clamps and make a vibration free mounting. The upper portion of the cover 9 comprises a dome shape sheet metal shell 45 which has an air outlet opening 46 adapted to receive a flexible hose or other conduit. The shell 45 is connected to the lower part 39 by bolts 47 and 48. The bolt 48 also serves to clamp the handle 10 against the lower part 39 of the cover. This handle has a rib 49 resting on the shell 45 and another screw bolt 50 extends through the handle of the shell 45 to secure the handle in place.

In order to clamp the parts to the dust pan 5, this pan is provided with ears 51 and 52 at diametrically opposite points thereon. Each ear pivotally supports a clamping lever 53 by means of a pivot pin 54. The clamping lever carries a curved spring clip 55, the clip being secured by a pin 56 in the clamping lever. As illustrated in Figure 3, the clip 55 can be hooked over the rim 17 of the cover 9 and then put under tension by lowering the clamping lever 53 so as to press the ring 14 between the rims 13 and 17.

From the foregoing description it is believed that the nature and advantages of my invention will be apparent to those skilled in this art. The main advantages of this construction hereinbefore described lie in the arrangement of the parts so that they can be readily separated and

cleaned without scattering the collected dust. When the housewife desires to remove the collected dust, she can release the clips 55, spread a piece of paper on the floor and set the cover unit 9, which carries all of the operating mechanism, on the piece of paper, leaving the dirt collecting parts of the cleaner free for removal and emptying. The filter is readily separable from the dust pan since it merely rests on the dust pan once the clips 55 are removed. This makes it easy to clean the filter and it leaves the dust pan entirely unobstructed for cleaning.

Having thus described my invention, I claim:

In combination a dust pan, a suction unit comprising a fan and a motor therefor, a cover carrying said suction unit entirely above the dust pan, the bottom edge of the cover and the top edge of the dust pan being substantially of the same shape and size, a filter cloth interposed between the dust pan and the suction unit, a ring carrying said filter cloth and having grooves receiving said edges and a screen at the bottom of the suction unit but above the ring cooperating with said ring to hold the filter cloth in extended position said cloth being provided with a spreading means overlying the first named ring, whereby to cause the cloth to spread out under the screen when suction is applied by the suction unit.

HARLEY J. McALLISTER.
